UNITED STATES PATENT OFFICE.

GEORGE E. KING, OF NEWTON, MASSACHUSETTS, ASSIGNOR TO THE GAMEWELL FIRE ALARM TELEGRAPH CO., OF NEW YORK, N. Y.

MULTIPLE-SIGNAL TRANSMITTER.

SPECIFICATION forming part of Letters Patent No. 727,543, dated May 5, 1903.

Application filed December 11, 1902. Serial No. 134,757. (No model.)

To all whom it may concern:

Be it known that I, GEORGE E. KING, of Newton, county of Middlesex, State of Massachusetts, have invented an Improvement in Multiple-Signal Transmitters, of which the following description, in connection with the accompanying drawings, is a specification, like characters on the drawings representing like parts.

This invention relates to multiple-signal transmitters having a pointer for operating a suitable controlling or selecting device for placing the transmitter in condition to transmit different signals, and has for its object to improve the construction of the means employed for holding or retaining the pointer in its several positions and also to improve the construction of the means employed for positively locking the pointer in its several different positions while the transmitter is operating, and also to improve the construction of the means employed for automatically restoring the pointer to its normal position.

The multiple transmitter herein shown, to which my invention is applied, is shown and described in my application for Letters Patent, Serial No. 14,308, filed April 25, 1900.

Figure 1 shows in front elevation a multiple-signal transmitter having a pointer and means embodying this invention for setting it to transmit the different signals. Fig. 2 is a rear elevation of the multiple-signal transmitter shown in Fig. 1. Fig. 3 is a plan view of the multiple-signal transmitter shown in Figs. 1 and 2, and Fig. 4 is a detail of the restoring device for the pointer-shaft.

In the particular form of multiple-signal transmitter herein shown, to which my invention is applied, a represents the signal-wheel, which is adapted to be rotated by a suitable train—as, for instance, said wheel is secured to a shaft a' , bearing a pinion a^2 , which is engaged by a toothed gear a^3 , secured to a sleeve a^4 , mounted loosely upon a shaft a^5 , and said toothed gear a^3 carries a pawl a^6 , which engages a ratchet-toothed wheel a^7 , secured to said shaft a^5 . The winding-arm b is secured to said shaft a^5 , by means of which said shaft is turned in one direction a partial revolution independently of the toothed gear a^3 , and a mainspring b' is connected to said shaft a^5 ,

which serves to restore it and at such times rotate the toothed gear a^3 . A toothed gear c is secured to the shaft a' , which engages a pinion c' , secured to a shaft c^2 , (see dotted lines, Fig. 3,) bearing an escape-wheel c^3 , with which co-operates a suitable pallet c^4 , secured to a shaft c^5 , carrying a fan c^6 . This train when operated is designed to impart to the signal-wheel a one complete revolution; yet in lieu of the train herein shown any other suitable form of construction of train or equivalent motor mechanism may be employed. The train is supported by the face-plates $d d'$, which are secured together by suitable posts. 65

The signal-wheel a is formed or provided with a signaling-surface on its edge for several different signals, and a circuit-operating device is adapted to be operated by said signal-wheel, which, as shown, consists of two contact-pens $f f'$, adapted to engage and disengage each other to make and break the circuit, one of said pens, as f , being rigidly secured to a pivoted block f^2 , and the other, as f' , being pivoted to said pivoted block f^2 and 75 acted upon by a spring f^5 , which moves it into engagement with the pen f . The contact-pens $f f'$ each have a contact-point f^{10} . A circuit-wire 2 is connected to one of said contact-pens and a circuit-wire 3 to the other. 80 The contact-pen f has a projection g and the contact-pen f' has a projection g' , and said projections are disposed one in advance of the other and adapted to engage the signal-wheel a , so that as the signal-wheel revolves 85 first one and then the other contact-pen will be moved.

A controlling or selecting device is provided whereby a number of different signals may be transmitted with but a single signal-wheel and a single pair of contact-pens, said controlling device being adapted to control the position of the contact-pens relative to the signal-wheel. The controlling device herein shown consists of a cam h , secured to a shaft h' , having its bearings in the frame $d d'$ and having attached to it a pointer h^2 , by means of which it may be turned at will, and the contact-pens $f f'$ are suitably extended and provided at their extremities with 95 projections $i i'$, which engage said cam h , and said projections $i i'$ are disposed one in ad-

vance of the other, like the projections g g' , and the cam h is designed to coöperate with either or both of said projections and also to be moved so as not to coöperate with either 5 one of said projections. As the cam h is turned by the pointer h^2 it will pass beneath the projections i i' and in its different positions will obstruct the movement of the contact-pens more or less in a direction toward 10 the signal-wheel a , except that in one position it will be out of coöperative engagement with both of said contact-pens; yet so far as my present invention is concerned any other suitable form of multiple-signal-transmitting 15 device may be employed. The pointer-shaft h' , bearing the cam h , is supported in its bearings in such manner as to be movable endwise or longitudinally for a short distance, and it has projecting laterally from it one or 20 more projections h^3 , which move over and continuously engage a toothed ring h^4 , stationarily secured to one of the face-plates, as d' , the teeth of said ring h^4 being made V-shaped or triangular, so that said projection 25 h^3 may move over the ring easily and when resting in any of the notches of said ring h^4 will hold the shaft from being too easily rotated. The teeth of the ring h^4 are disposed to hold the shaft h' , with its cam h , in the 30 several different positions required for the transmission of the different signals. A spring h^5 is mounted upon said shaft h' between the plate d and a block j^2 on said shaft, which tends to throw said shaft forward and 35 hold it with its projection h^3 in free engagement with the toothed ring. As the pointer is turned the shaft will be rapidly moved endwise against the action of said spring by the projection h^3 passing over the teeth of the ring 40 h^4 ; but this movement of the shaft is merely incidental. As a means of restoring said shaft to its normal position a restoring-spring j is provided, which is attached at one end to a post j^{10} and at the opposite end to one 45 end of a flexible band j' , the opposite end of said band being secured to the block j^2 , which is secured to the shaft h' . The restoring-spring is made strong enough to draw upon the block j^2 and turn the shaft h' whenever 50 the projections h^3 are moved out of the notches of the toothed ring, the shaft at such time being unrestrained, and therefore free to rotate. The projections h^3 are removed from the notches of the ring h^4 by the endwise 55 movement of the shaft h' , which is accomplished by closing the door A of the box against the outer end of said shaft, said door in Fig. 3 being represented as part way open. Thus it will be seen that the signal may be 60 set by the pointer and the train started by the actuating-arm b and that by closing the door of the box the shaft h' will be moved endwise, its projections h^3 moved out of the notches of the stationary ring h^4 , and the restoring-spring j permitted to act and restore 65 the pointer-shaft.

It is desirable to provide means for locking

the pointer-shaft in fixed position while the transmitter is operating, so that the pointer will not be accidentally moved during such 70 time and a mixed signal transmitted, and, furthermore, it is necessary that a locking device be provided for the pointer-shaft when the restoring device for said pointer-shaft is adapted to be operated by closing the door 75 of the box in order that the pointer will not be at once restored as soon as the door is closed unless the signal has been transmitted. Therefore the locking device for the pointer-shaft herein shown is adapted to lock said 80 shaft and hold it while the signal is being transmitted, notwithstanding the door of the box may have been previously closed. The locking device consists of an arm k , mounted loosely upon the shaft a^5 , having a detent at 85 its outer end which engages either one of a number of notches k^{10} , cut or formed in the edge of the ring k' which is secured to the pointer-shaft h' , and said detent-arm k is normally held out of engagement with said ring 90 by a projection k^2 , secured to the winding-shaft a^5 , as shown in Fig. 1, and when occupying this position the pointer-shaft is free to be turned; but whenever the winding-arm 95 is operated and the shaft a^5 consequently turned the projection k^2 will be moved away from the detent-arm k , and said detent-arm will then be at once drawn into engagement with the toothed ring k' by means of a spring 100 k^3 , which is connected to it, and when the detent-arm k thus engages the toothed ring k' the pointer-shaft is locked. The detent-arm will remain in engagement with the toothed ring k' until the winding-arm resumes its normal position, for as said winding-arm resumes its normal position the projection k^2 will engage said detent-arm k and disengage it from the toothed ring k' . As soon as the toothed ring is disengaged the 105 pointer-shaft is free to return to its normal position and will be so returned as soon as said shaft is moved endwise and the restoring-spring permitted to act. If the door of the box should be closed before the signal has been completely transmitted and the pointer-shaft thereby moved endwise, the detent-arm k will still hold the pointer-shaft locked by 110 engaging the toothed ring k' , and said shaft will not be restored until the winding-arm has resumed its normal position and has moved the detent-arm out of engagement with the toothed ring. 115

m represents a stop-pin for the pointer-shaft, which is engaged by the toothed ring k' when said shaft resumes its normal position. 120

Having thus described my invention, what I claim as new, and desire to secure by Letters Patent, is—

1. In a multiple-signal transmitter, the combination with a signaling-train and a controlling device, of a longitudinally-movable shaft connected with said controlling device, a pointer secured thereto, projections on said shaft, a stationarily-disposed toothed ring 130

which is engaged by said projections, and a spring for moving the shaft in a direction toward said toothed ring, substantially as described.

5 2. In a multiple-signal transmitter, a signaling-train, a pointer for setting the operating parts of the transmitter in position to transmit the different signals, a rotatable and longitudinally-movable shaft to which said pointer is secured, a stationary ring having V-shaped teeth, one or more projections on the pointer-shaft which coöperate with the teeth of said ring, and a spring for restoring the pointer-shaft to its normal position whenever said projections disengage the ring, substantially as described.

20 3. In a multiple-signal transmitter, a signaling-train, a pointer for setting the operating parts of the transmitter in position to transmit the different signals, a rotatable and longitudinally-movable shaft to which said pointer is secured, a stationary ring having V-shaped teeth, one or more projections on the pointer-shaft which coöperate with the teeth of said ring, and a spring for pressing said shaft longitudinally to cause said projections to engage with the teeth of said ring and thereby hold said shaft in different predetermined positions, substantially as described.

25 4. In a multiple-signal transmitter, a signaling-train, a pointer, a rotatable and longitudinally-movable shaft to which it is se-

cured, an engaging device for frictionally holding said shaft in its different positions, 35 into and out of engagement with which it is moved by longitudinal movement thereon, a spring connected to said shaft for restoring it when disengaged from said engaging device, substantially as described.

40 5. In a multiple-signal transmitter, a signaling-train, a pointer-shaft bearing a pointer, a toothed ring secured to said shaft, a pivoted detent-arm, a spring for moving said arm into engagement with said ring, a winding-shaft for the signaling-train bearing a winding-arm and means operated by it for moving said detent-arm out of engagement with said ring, substantially as described.

45 6. In a multiple-signal transmitter, a signaling-train, a pointer-shaft bearing a pointer, a toothed ring secured to said shaft, a pivoted detent-arm, a spring for moving said arm into engagement with said ring, a winding-shaft for the signaling-train bearing a winding-arm, and a projection on said winding-shaft which engages said detent-arm and moves it out of engagement with said ring, 55 substantially as described.

50 In testimony whereof I have signed my name to this specification in the presence of two subscribing witnesses.

GEORGE E. KING.
